(57) **CLAIM**

The ornamental design for a golf club training head, as shown and described.

DESCRIPTION

FIG. 1 is a front right and bottom perspective view of one embodiment of our golf club training head;

FIG. 2 is a front left and top perspective view, thereof;

FIG. 3 is a left rear perspective view thereof;

FIG. 4 is a bottom plan view thereof;

FIG. 5 is a top plan view thereof; and,

FIG. 6 is a left rear perspective view of a second embodiment of the golf club training head as disclosed in FIG. 1. The undisclosed sides being identical to FIGS. 1, 2, 4 and 5. The broken lines showing in the attached drawings are for illustrative purposes only and form no part of the claimed design.
